UNITED STATES PATENT OFFICE.

JAMES BARKER, OF DETROIT, MICHIGAN.

ARM-REST FOR BOOKS.

SPECIFICATION forming part of Letters Patent No. 700,006, dated May 13, 1902.

Application filed August 14, 1901. Serial No. 72,082. (No model.)

To all whom it may concern:

Be it known that I, JAMES BARKER, a citizen of the United States, residing at Detroit, in the county of Wayne and State of Michigan, have invented certain new and useful Improvements in Arm-Rests for Books, of which the following is a specification, reference being had therein to the accompanying drawings.

The invention relates to new and useful improvements in arm-rests for books; and it consists in the construction of an arm-rest adapted to be used upon the end of a book and in the construction and arrangement hereinafter more fully set forth, illustrated in the drawings, and particularly pointed out in the claims.

In the drawings, Figure 1 is a perspective view of my improved device as applied in use to the lower edge of a book, such as a ledger. Fig. 2 is a detached perspective view of the support for the rest-plate, showing the hook for holding the support in proper relation to the end of the book. Fig. 3 is a perspective view showing the guide-bars and the sliding blocks thereon forming a double adjustable support for the arm-rest. Fig. 4 is an edge elevation of the longitudinal guide-bar and the sliding block thereon.

A represents an open book, of which B represents the covers, the book being of known construction. Between the covers and near the back is a cross-bar C, over which engages a hook-plate D, which hook-plate extends up over the base-plate or base E, which is adapted to engage the back of the book, either inside or outside, as may be desired. In the construction herein illustrated I have shown it as adapted to engage on the outside of the back of the book. Extending upward from the end of the base-plate E is a standard F, the upper end of which is secured to a longitudinal guide-bar G.

H is a block sliding on the guide-bar, and as the bar is of sufficient length to extend across the back and upon both sides thereof it is obvious that the block may be slid along across the end of the book and beside the end of either cover. Secured to the block H is a transverse guide-bar I, upon which slidingly engages a rest-plate block J, this block being movable on its guide-bar to and from the end of the book.

K is a rest-plate for the arm which is hinged to the rest-plate block J. The hinge I have shown embodies a multiple of hinge-sections a, hinged together and to the arm-rest block and the arm-rest, so as to make what I call a "multiple" hinge. This particular construction of multiple or extensible hinge is not necessary, as any form of device which will enable the arm-rest to turn about various points or to hinge at various heights above its block will answer the requirements of my invention.

The arm-rest preferably has an extension L at its inner edge extending beyond its hinged joint, so that it may be engaged over the lower edge of the leaves of the book when open, as plainly shown in Fig. 1.

The parts being thus constructed, their operation is as follows: The book being open, in order to turn the leaves freely the operator moves the arm-rest K so that its extension L will be clear of the leaves of the book. This is accomplished by sliding the arm-rest and its block J upon the transverse guide-bar I. The leaves may then be turned freely without contact with the arm-rest until the desired point is reached, and then the rest can be again lifted and moved inward until the extension L bears upon the lower end of the leaves.

It is evident that by means of an extensible or movable hinge the arm-rest may be supported upon the edge of the leaves at any desired height or thickness of leaves—i. e., at any point where the book may be opened—without any binding or straining of the hinge-joint.

When it is desired to use the arm-rest upon the opposite leaf to that upon which it is shown in Fig. 1, the operator simply slides the block H to the right, which of course will carry with it the arm-rest, and then turns the rest upon its hinge to the right, and it will be applied to the right-hand part of the book in the same manner as now shown in Fig. 1 as applied to the left.

To disengage the device from the book, the hook D is detached from the cross-bar C, when it is perfectly free to be removed without further manipulation.

What I claim as my invention is—

1. The combination with a book, of a member secured to the end thereof, a support detachably connected to said member, and an arm-rest mounted upon the support for lon-

itudinal movement along the edge of the book.

2. The combination with a book, of a transverse member secured to the book at one end thereof, a support detachably connected to said member, a longitudinal guide-bar upon the support, an arm-rest, and connections between said guide-bar and arm-rest permitting movement of the latter along the lower edge of the book.

15 3. In an arm-rest for books, the combination of a support, a longitudinal guide-bar thereon, a sliding block movable on the guide-bar, a transverse guide-bar on the sliding block, the arm-rest block sliding thereon, and the multiple-hinged arm-rest on said block.

20 4. In an arm-rest for books, the combination of a support, a longitudinal guide-bar thereon, a sliding block movable on the guide-bar, a transverse guide-bar on the sliding block, the arm-rest block sliding on the transverse

guide-bar and the slidingly-hinged arm-rest on said block.

5. In an arm-rest for books, a support for the hinged arm-rest comprising a base adapted to engage the book-cover, a transverse bar at the end of the book, and a hook adapted to engage the bar.

25 6. In an arm-rest for books, the combination of a base adapted to engage beneath the book-cover, a transverse bar at the end of the book extending across between the covers, an upright hook engaging the bar, a standard beside said hook, and an arm-rest supported upon the standard.

30 In testimony whereof I affix my signature in presence of two witnesses.

35 JAMES BARKER.
